APPARATUS FOR RAILWAY TRAIN COMMUNICATION SYSTEMS

Willard P. Place, Wilkinsburg, Pa., assignor to
The Union Switch & Signal Company, Swiss-
vale, Pa., a corporation of Pennsylvania

Application April 12, 1940, Serial No. 329,321

17 Claims. (Cl. 246—8)

My invention relates to apparatus for railway train communication systems, and more particularly to apparatus for railway train communication systems which use the track rails as a part of the transmitting circuit.

Railway train communication systems for telephone communication between a station located on a vehicle of a train such as a locomotive of a freight train, and another station remote therefrom, such as a station located in the caboose of the freight train, are in use. Telephone current is applied to the track rails at the sending station either inductively through the medium of an inductor mounted for inductive relation with the rails or conductively through the medium of a circuit having contact with the rails. The current flows in the rails in both directions from the point at which it is applied thereto and returns through the ground and other conductors. At the receiving station current is received from the rails through the medium of a circuit element either inductively or conductively coupled with the track rails. When the track rails are formed into consecutive insulated track sections for either or both wayside and cab signal systems the insulated rail joints may interfere with the effective transmission of the train telephone current because such telephone current must at times flow from the rails of one track section to the rails of an adjoining track section.

Accordingly, a feature of my invention is the provision of novel and improved apparatus for conducting such communication current around the insulated rail joints which separate two track sections and wherewith interference to the operation of the usual wayside and cab signal systems is avoided.

Another feature of my invention is the provision of novel and improved apparatus of the type herein contemplated wherewith the track rails of adjoining insulated sections are shunted and the insulated rail joints separating the sections are by-passed in such a manner that noise in the telephone apparatus caused by current surges produced by the train wheels running on and off the insulated rail joints is substantially eliminated.

The above features, as well as other advantages of apparatus embodying my invention, I attain by providing low resistance by-pass or shunt circuits one around each insulated rail joint separating two track sections and each of which circuits is controlled by at least one of the track relays of the adjoining sections so that the by-passed circuits are closed only while a train is

passing from one section into the other. Each of such by-pass circuits is periodically interrupted so that when a train vacates the rear section of such adjoining sections the track relay of such section is reenergized in the usual manner during the first interval the by-pass circuits are interrupted and hence the usual train signaling devices are restored to their normal condition with little or no delay due to the by-pass circuits. Furthermore, I preferably provide an auxiliary relay having the heels of four contact fingers connected together and their front contacts one connected to each of the four rails of the two adjoining sections. Thus the four rail ends of the two adjoining track sections are connected to a common point thereby short circuiting the rails of each section and by-passing the insulated rail joint when the auxiliary relay is picked up. This auxiliary relay is controlled by the track relays of the associated track sections and also by a contact of a coding device such as the code transmitter of one of the sections when coded current is supplied at times to the track circuit for control of either or both wayside and cab signals.

I shall describe two forms of apparatus embodying my invention, and shall then point out the novel features thereof in claims.

In the accompanying drawing Figs. 1 and 2 are diagrammatic views showing two different forms of apparatus each of which embodies my invention when used with track sections having track circuits supplied normally with non-coded alternating current for control of wayside signals and which track circuits are supplied with coded alternating current when a train occupies an associated section for control of cab signals. In each of the two views like reference characters designate similar parts.

It will be understood that my invention is not limited to this one arrangement of track circuits for insulated track sections, but serves to illustrate the general application of apparatus embodying my invention.

Referring to Fig. 1, the reference characters $1a$ and $1b$ designate the track rails of a stretch of railway over which traffic normally moves in the direction indicated by an arrow and which rails are formed by the usual insulated rail joints 2 into consecutive track sections of which sections only the one section $A-B$ and the adjacent ends of the two adjoining sections are shown for the sake of simplicity, since these are sufficient for a full understanding of my invention. Each track section is provided with a track circuit for con-

trolling both wayside and cab signals and each of which track circuits comprises a source of current connected across the rails at one end of the section and a track relay connected across the rails at the other end of the section. The type of track circuit is immaterial, and may be any one of the well-known forms in present day use. The track circuits would be preferably alike and a description of the track circuit for section A—B will serve for an understanding of all. As shown in Fig. 1, the track circuit of section A—B is normally supplied with non-coded alternating current of the frequency of 60 cycles per second for the control of an alternating current track relay which governs a wayside signal. The track circuit is supplied with alternating current of the frequency of 100 cycles per second coded at a predetermined code rate for control of a cab signal when a train occupies the section, such coded alternating current being in accordance with traffic conditions in advance of the section. The immediate source of current for the track circuit of section A—B is a track transformer T₁ whose secondary winding 3 is connected across the rails adjacent the exit end of section A—B over wires 4 and 5 with a current limiting reactor 6 interposed in wire 5. The primary winding 7 of track transformer T₁ is normally supplied, that is, when section A—B is unoccupied, with 60 cycle alternating current from the secondary winding 8 of a line transformer T₂ whose primary winding 9 is connected with a generator, not shown, adaptable of supplying alternating current of the frequency of 60 cycles per second. To be explicit, the secondary winding 8 of transformer T₂ is connected across two bus terminals BX and CX and primary winding 7 of track transformer T₁ is connected across the bus terminals BX and CX by a circuit which can be traced from terminal BX over wire 15, back contact 16 of a relay VB to be later referred to, wire 17, primary winding 7 of transformer T₁ and wire 18 to terminal CX.

When the track section A—B is occupied, the primary winding 7 of track transformer T₁ is disconnected from the 60 cycle source of current in a manner to later appear and is connected with the secondary winding 10 of another line transformer T₃ whose primary winding 11 is connected with a generator, not shown, adaptable of supplying alternating current at the frequency of 100 cycles per second, such 100 cycle alternating current being coded at a predetermined code rate, as will presently appear.

A track relay ATR responsive to 60 cycle alternating current is connected across the rails adjacent the entrance end of section A—B over wires 12 and 13. Hence track relay ATR is normally energized to control a wayside signal for governing traffic through section A—B. Such wayside signal is not shown since it forms no part of my invention and may be any one of the several well-known types of wayside signals. Track relay ATR when energized and picked up opens a back contact 14 interposed in a line circuit for an approach control relay VB as will be readily understood by an inspection of Fig. 1. When a train enters section A—B to shunt the track relay ATR, this relay is released to close back contact 14 whereupon approach control relay VB is energized and picked up to open back contact 16 and close front contacts 19, 20 and 21. The opening of back contact 16 removes the normal supply of 60 cycle alternating current from primary winding 7 of track transformer T₁. The closing of

front contact 19 completes a simple circuit easily traced for the motor winding 22 of a code transmitter CT and code transmitter CT is operated.

The code transmitter CT may be of any one of several types well-known in the art and is here shown as being of the motor type. When motor winding 22 of code transmitter CT is energized a shaft indicated by a dotted line 23 is rotated at a predetermined rate of, say, for example, 15 revolutions per minute. A cam 24 is mounted in fixed relation on shaft 23 and rotates at 15 revolutions per minute, cam 23 being preferably of suitable insulating material. The cam 24 is constructed with 8 teeth and has associated therewith a code contact member 26, the arrangement being such that contact member 26 is biased by any convenient means to engage the outer surface of cam 24 so as to be actuated by each tooth of the cam. A contact 120—120a is closed when contact member 26 is actuated by a tooth of cam 24 and a contact 120—120b is closed when contact member 26 is in the space between two teeth of the cam. It follows that contacts 120—120a and 120—120b are periodically opened and closed at the code rate of 120 times (15×8) per minute as long as motor winding 22 of code transmitter CT is energized.

A second shaft indicated by a dotted line 23a is operatively connected with shaft 23 through a gear train indicated conventionally at 27, and a cam 25 of suitable insulated material is fixed on shaft 23a, the arrangement being such that shaft 23a and cam 25 are rotated at a rate of, say, 4 revolutions per minute as long as the code transmitter CT is operated. Cam 25 is provided with a depressed portion 28 and has associated therewith a contact member 29, which member is biased to engage the outer surface of the cam with the result that a contact 30—31 is operated by contact member 29, the contact 30—31 being normally closed and opened when the contact member 29 engages the depressed portion 28. The depressed portion 28 of cam 25 is proportioned so that the interval it is adjacent contact member 29 and contact 30—31 is open is of the order of one second or somewhat greater than the cycle interval of the code rate effected by cam 24.

It is to be understood, of course, that my invention is not limited to the specific code rates here specified for the contact member 26 operated by cam 24 or to the specific period the contact 30—31 operated by cam 25 is open and these intervals are given by way of illustration as an aid to a clearer understanding of my invention.

The contact 120—120a is interposed in a circuit which connects secondary winding 10 of transformer T₃ with primary winding 7 of track transformer T₁, the circuit comprising right-hand terminal of secondary winding 10, front contact 20 of relay VB when that relay is picked up in the manner explained hereinbefore, contact 120—120a, wire 17, primary winding 7, wire 18 to bus terminal CX and thence to the left-hand terminal of secondary winding 10. Consequently, when a train enters section A—B to shunt relay ATR and pick up approach control relay VB, which in turn causes code transmitter CT to be active and disconnects the normal source of 60 cycle alternating current, alternating current of 100 cycles per second coded at the rate of 120 interruptions per minute is supplied to the track circuit of section A—B. It is to be understood, of course, that this coded current is in actual practice also governed by traffic condi-

tions in advance of section A-B by any of the well-known means but which control is not shown for the sake of simplicity since it forms no part of my invention.

5 The contact 120-120b is interposed in a second circuit over which the primary winding 7 of track transformer T' is connected across the bus terminals BX and CX for supplying alternating current of 60 cycles per second to the track circuit. This second circuit extends from terminal BX, over wire 15, a back contact 32 of a track relay BTR for the track circuit of the section next in advance of section A-B, contact 120-120b, wire 17, primary winding 7 and wire 18 to terminal CX.

From the foregoing description of the track circuit of section A-B it is to be seen that normally non-coded alternating current of 60 cycles per second is supplied to the track circuit for energizing track relay ATR; when a train enters section A-B to shunt relay ATR the approach control relay VB is picked up to disconnect the 60 cycle source and to cause coded 100 cycle current to be supplied to the track circuit; when 25 the train moves into the section next in advance of the section A-B to shunt track relay BTR, 60 cycle alternating current is applied to the track circuit of section A-B during each off period of the coded 100 cycle current and when the train vacates section A-B track relay ATR is reenergized with the result that approach control relay VB is released to discontinue operation of code transmitter CT and cause non-coded current to be supplied to the track circuit of section A-B. 30 The apparatus of track circuit of section A-B thus far described is that in general use except cam 25 of the code transmitter CT and the parts associated with cam 25.

I shall now describe the apparatus embodying my invention as it is applied to the track circuit of section A-B. An auxiliary relay AB of the type responsive to 60 cycle alternating current is controlled over a circuit including terminal BX, wire 15, front contact 21 of approach control relay VB, back contact 33 of track relay BTR, contact 30-31 of code transmitter CT, wire 34, winding of relay AB and to terminal CX. Hence when approach control relay VB has been picked up in response to a train occupying section A-B and the head end of the train moves into the section next in advance to shunt track relay BTR, the auxiliary relay AB is picked up except for the interval the depressed portion 28 of cam 25 is adjacent contact member 29 and contact 30-31 is open. In other words when a train occupies both section A-B and the section next in advance the auxiliary relay AB is picked up except for recurrent intervals during each of which intervals relay AB is released. Furthermore, it is to be noted that the intervals at which the auxiliary relay AB is released are relatively far apart and each interval is somewhat greater than the cycle interval of the coded current supplied to the track circuit of section A-B. Also when the track relay ATR is reenergized to cause approach control relay VB to be released opening front contact 21 the auxiliary relay AB is deenergized and released.

70 Auxiliary relay AB is provided with four contact fingers 35, 36, 37 and 38. The so-called heels of these contact fingers are all joined to a conductor 39. The front contact 40 of contact finger 35 is connected over wire 41 to rail 1a to the right of the insulated rail joint 2 inter-

posed in rail 1a to electrically separate rail 1a of section A-B from the corresponding rail of the section next in advance. In like manner the front contact 42 of contact finger 36 is connected over wire 43 with rail 1b to the right of the insulated rail joint 2 interposed in rail 1b between section A-B and the section next in advance. The front contact 44 of contact finger 37 is connected over wire 45 with rail 1b to the left of the insulated rail joint 2 interposed in that rail 10 and front contact 46 of contact finger 38 is connected over wire 47 with rail 1a to the left of the insulated rail joint 2 interposed in that rail. It is to be seen, therefore, that when relay AB is picked up closing front contacts 40, 42, 44 15 and 46, the rails 1a and 1b of section A-B are shunted over a circuit involving wire 47 connected to rail 1a, front contact 46, contact finger 38, conductor 39, contact finger 37, front contact 44 and wire 45 to rail 1b. Also the rails 1a 20 and 1b of the section next in advance are shunted over wire 41 connected to rail 1a, front contact 40, contact finger 35, conductor 39, contact finger 36, front contact 42, and wire 43 to rail 1b. 25

At the same time a low resistance circuit shunts the insulated rail joint 2 of rail 1a at location B, the circuit including wire 41 connected to the rail to the right of the insulated rail joint, front contact 40, contact finger 35, conductor 39, contact finger 38, front contact 46 and wire 47 to rail 1a to the left of the insulated joint.

In like fashion a low resistance by-pass circuit bridges the insulated rail joint 2 interposed in rail 1b at location B, the circuit including wire 43 connected to the rail to the right of the insulated rail joint, front contact 42, contact finger 36, conductor 39, contact finger 37, front contact 44 and wire 45 to rail 1b to the left of the insulated rail joint. It follows that when a train spans the insulated rail joints at location B to occupy both section A-B and the section next in advance and auxiliary relay AB is picked up, each insulated rail joint 2 at location B is bypassed by a low impedance circuit and any communication current applied to the rails at some point along the section next in advance of section A-B will flow to the rails of section A-B with substantially no impedance at the insulated rail joints at location B. Also communication current applied to the rails at any point along section A-B flows to the rails of the section next in advance with substantially no interference at the insulated rail joints at location B. Since the ends of all four of the rails at location B are connected to a common point (conductor 39) the moving of the train wheels on and off the insulated rail joints will not materially vary the flow of the communication current and noise in the telephone receiving apparatus due to surging of the telephone current is substantially eliminated. 50 55

When the rear of the train vacates section A-B, the shunt or by-pass circuits controlled by relay AB do not materially interfere with the reenergizing of the track relay ATR since the first time the contact 30-31 of code transmitter CT is opened the auxiliary relay AB is released with the result that the 60 cycle alternating current applied to the track circuit of section A-B over contact 120-120b of the code transmitter is effective to reenergize the track relay ATR causing the approach control relay VB to be released, after which the auxiliary relay AB remains deenergized and the by-pass or 70 75

shunt circuits controlled thereby are open. I have found that such by-pass circuits around a pair of insulated rail joints may be periodically opened in the manner effected by the code transmitter contact 30-31 without materially interfering with the transmitting of the telephone current.

Referring to Fig. 2, the track rails 1a and 1b are formed by insulated rail joint 2 with a track section A-B provided with a track circuit the same as in Fig. 1 and the description thereof will not be repeated. In Fig. 2, low resistance by-pass circuits around the insulated rail joints separating section A-B from the section next in advance are completed by contacts operated by the code transmitter CT and auxiliary relay AB is omitted. Looking at Fig. 2, the code transmitter CT is provided with a second cam 50 fixed on shaft 23a the same as cam 25, the cam 50 being constructed similar to cam 25 and formed with a depressed portion 51 substantially like the depressed portion 28 of cam 25. Cam 50 is associated with a contact member 52 for operating a contact 53-54 and which contact 53-54 is normally closed and is opened only during the interval contact member 50 is adjacent the depressed portion 51.

A shunt or by-pass circuit around insulated rail joint 2 in rail 1a at location B can be traced from rail 1a of section A-B over wire 55, front contact 56 of approach control relay VB, contact 30-31 of code transmitter CT, back contact 33 of track relay BTR and wire 57 to rail 1a of the section next in advance. A similar shunt or by-pass circuit around the insulated rail joint 2 of rail 1b can be traced from rail 1b to the left of the insulated rail joint over wire 59, front contact 60 of approach control relay VB, contact 53-54 of code transmitter CT, back contact 61 of track relay BTR and wire 62 to rail 1b to the right of the insulated rail joint.

Hence when a train occupies both section A-B and the section next in advance, to shunt both relays ATR and BTR, the by-pass circuits around the insulated rail joints 2 at location B are closed and telephone current applied to the rails of either section is transmitted to the rails of the other section with substantially no impedance at the insulated rail joints at location B. When the rear of a train vacates section A-B of Fig. 2, the by-pass circuits are opened periodically by the contacts 30-31 and 53-54 of the code transmitter so that the 60 cycle alternating current applied to the track circuit of section A-B over contact 120-120b of the code transmitter is effective to reenergize the track relay ATR and restore the apparatus associated with that track circuit to its normal position. In Fig. 2 the rails of the two sections are not shunted as is the case of Fig. 1.

Although I have herein shown and described only two forms of apparatus embodying my invention, it is understood that various changes and modifications may be made therein within the scope of the appended claims without departing from the spirit and scope of my invention.

Having thus thus described my invention, what I claim is:

1. In apparatus for use with a system providing communication between a station located on a vehicle of a railway train and a remote station over a transmitting circuit including the track rails when the track rails are formed into consecutive insulated track sections each of which is provided with a track circuit supplied with

current for energizing a track relay, the combination comprising, a coding device for a given track section operative at times to recurrently open a normally closed contact, and circuit means including said contact of said coding device and a contact governed by the track relay for the track circuit of said given section as well as a contact governed by the track relay for the track circuit of the track section next in advance of said given section to shunt the insulated rail joints which separate said given section from said section next in advance.

2. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, a coding device for a given track section having a contact which is periodically opened and closed, a first normally open contact which becomes closed when a train occupies said given section, a second normally open contact which becomes closed when a train occupies the section next in advance of said given section, and circuit means including said contact of said coding device, and said first and second normally open contacts and connected with the track rails to bridge around the insulated rail joints separating said given section and said section next in advance.

3. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, a coding device for a given track section operative to open a normally closed contact at recurrent intervals, and circuit means including said contact of said coding device and a back contact of the track relay for the track circuit of the track section next in advance of said given section to form by-pass circuits around each of the insulated rail joints separating said given section and said section next in advance.

4. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, by-pass circuit means connected to each rail on each side of the insulated rail joints separating a given track section and the section next in advance of said given section to provide when closed low impedance paths around such insulated rail joints, a code transmitter for said given track section operated at times to periodically open and close a contact, and said code transmitter contact interposed in said by-pass circuit means.

5. In apparatus for use with a system providing communication between a station located on a vehicle of a railway train and a remote station over a transmitting circuit including the track rails when the track rails are formed into consecutive insulated track sections each of which is provided with a track circuit supplied with

current for energizing a track relay, the combination comprising, an approach control relay governed by the track relay of a given track section to a first position when said given section is unoccupied and to a second position when said given section is occupied, a code transmitter effective when energized to periodically open and close a contact, a circuit including a second position contact of said control relay to energize said code transmitter, and circuit means including a second position contact of said control relay and said code transmitter contact and having connections to the rails at each side of the insulated rail joints separating said given section and the section next in advance of said given section to form low impedance paths around such insulated rail joints.

6. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an approach control relay governed by the track relay of a given track section to a first position when said given section is unoccupied and to a second position when said given section is occupied, a code transmitter effective when energized to periodically open and close a first and a second contact in step with each other, a circuit including a second position contact of said control relay to energize said code transmitter; a first by-pass circuit including a second position contact of said control relay, a back contact of the track relay for the track section next in advance of said given section and said first code transmitter contact and connected to each side of the insulated rail joint separating one of the track rails of said given section and the corresponding rail of said section next in advance; and a second by-pass circuit including a second position contact of said control relay, a back contact of the track relay for said section next in advance and said second code transmitter contact and connected to each side of the insulated rail joint separating the other track rail of said given section and the corresponding rail of said section next in advance.

7. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an approach control relay governed by the track relay of a given track section to a first position when said given section is unoccupied and to a second position when said given section is occupied, a first by-pass circuit including a second position contact of said control relay and a back contact of the track relay for the track section next in advance of said given section connected to one of the track rails to each side of the insulated rail joint interposed in said one track rail to separate said given section and said section next in advance, and a second by-pass circuit including a second position contact of said control relay and a back contact of the track relay for said section next in advance connected to the other track rail to each side of the insulated rail joint interposed in said

other track rail to separate said given section and said section next in advance.

8. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an approach control relay governed by the track relay of a given track section to a first position when said given section is unoccupied and to a second position when said given section is occupied, a first by-pass circuit including a second position contact of said control relay and a back contact of the track relay for the track section next in advance of said given section connected to one of the track rails to each side of the insulated rail joint interposed in said one track rail to separate said given section and said section next in advance, a second by-pass circuit including a second position contact of said control relay and a back contact of the track relay for said section next in advance connected to the other track rail to each side of the insulated rail joint interposed in said other track rail to separate said given section and said section next in advance, and means for periodically opening each of said by-pass circuits.

9. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, a coding device for a given track section effective when energized to periodically open and close a contact, an auxiliary relay for said given section, means including a contact of the track relay of said given section for energizing said coding device, an energizing circuit including said contact of the coding device and a contact of the track relay for the section next in advance of said given section to energize said auxiliary relay, and two by-pass circuits one for shunting around each of the insulated rail joints separating said given section and said section next in advance and each of which by-pass circuits includes a front contact of said auxiliary relay.

10. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an auxiliary relay for a given track section, a first by-pass circuit including a front contact of said auxiliary relay connected to one of the track rails at each side of the insulated rail joint interposed in said one rail between said given track section and the section next in advance, a second by-pass circuit including a front contact of said auxiliary relay connected to the other track rail at each side of the insulated rail joint interposed in said other rail between said given section and the section next in advance, an energizing circuit means including a contact of the track relay for said given section and a contact of the track relay for the section next in advance for energizing

- said auxiliary relay, and other means for periodically rendering said energizing circuit means ineffective to energize said auxiliary relay.
11. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an approach control relay and an auxiliary relay for a given track section, circuit means controlled by traffic conditions of said given section to operate said approach control relay to a first position or a second position according as said given section is unoccupied or occupied, an energizing circuit including a second position contact of said control relay and a back contact of the track relay for the section next in advance of said given section to energize said auxiliary relay, by-pass circuit means including a front contact of said auxiliary relay connected to each track rail to each side of the insulated rail joints separating said given section and said section next in advance, and coding means controlled over a second position contact of said control relay operative to periodically interrupt said energizing circuit.
12. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an auxiliary relay for a given track section and which relay is provided with four contact fingers having their heels all connected together by a single conductor, a first circuit including the front contact of a first and a second of said contact fingers connected across the rails of said given section, a second circuit including the front contact of a third and a fourth of said contact fingers connected across the rails of the section next in advance of said given section, said first and second circuits together with said single conductor forming a by-pass circuit around each insulated rail joint separating said given section and said section next in advance when said auxiliary relay is picked up, an energizing circuit controlled over a back contact of the track relay for said given section and a back contact of the track relay for said section next in advance to pick up said auxiliary relay, and a coding device having a contact interposed in said energizing circuit to cause said auxiliary relay to be periodically released.
13. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an auxiliary relay for a given track section and which relay is provided with four contact fingers having their heels connected together to form a common terminal, front contacts of a first and a second of said four contact fingers connected across the rails of said given section and front contacts of a third and a fourth of said contact fingers connected across the rails of the

section next in advance of said given section to provide shunt paths around the insulated rail joints separating said given section from said section next in advance, and an energizing circuit including a first contact responsive to traffic conditions of said given section and a second contact responsive to traffic conditions of said section next in advance to energize said auxiliary relay.

14. In apparatus for use with a system providing communication between a station located on a vehicle of a railway train and a remote station over a transmitting circuit including the track rails when the track rails are formed into consecutive insulated track sections and each of which is equipped with a track circuit supplied with current from one source to energize a track relay when the section is unoccupied and with current from another source coded over a code transmitter contact operated at a predetermined code rate when the section is occupied, the combination comprising, another contact operatively mounted on the code transmitter of a given track section to be closed except for recurrent intervals each of which intervals is greater than the cycle interval of said code rate, and circuit means including said other contact to bridge around the insulated rail joints separating said given section and the section adjacent thereto.

15. In apparatus for use with a system providing communication between a station located on a vehicle of a railway train and a remote station over a transmitting circuit including the track rails when the track rails are formed into consecutive insulated track sections and each of which is equipped with a track circuit supplied with current from one source to energize a track relay when the section is unoccupied and with current from another source coded over a code transmitter contact operated at a predetermined code rate when the section is occupied, the combination comprising, another contact operatively mounted on the code transmitter of a given track section to be closed except for recurrent intervals each of which intervals is slightly greater than the cycle interval of said code rate, and circuit means including said other contact and a back contact of the track relay for the section next in advance of said given section to by-pass the insulated rail joints separating said given section and said section next in advance.

16. In apparatus for use with a system providing communication between a station located on a vehicle of a railway train and a remote station over a transmitting circuit including the track rails when the track rails are formed into consecutive insulated track sections each of which is provided with a track circuit supplied with current for energizing a track relay, the combination comprising, an approach control relay governed by the track relay of a given track section to a first position when said given section is unoccupied and to a second position when said given section is occupied, a first by-pass circuit controlled over a second position contact of said approach control relay and a back contact of the track relay for the track section next in advance of said given section and connected to one of the track rails to each side of the insulated rail joint interposed in said one track rail to separate said given section and said section next in advance, and a second by-pass circuit controlled over a second position contact of said approach control relay and a back con-

tact of the track relay for said section next in advance and connected to the other track rail to each side of the insulated rail joint interposed in said other track rail to separate said given section and said section next in advance.

17. In apparatus for use with a system providing communication between a station located on a vehicle of a railway train and a remote station over a transmitting circuit including the 10 track rails when the track rails are formed into consecutive insulated track sections each of which is provided with a track circuit supplied with current for energizing a track relay, the combination comprising, an approach control

relay governed by the track relay of a given track section to a first position when said given section is unoccupied and to a second position when said given section is occupied, and two by-pass circuits one connected around each of the two insulated rail joints interposed one in each track rail to separate said given track section from the section next in advance and each of which by-pass circuits is controlled by a second position contact of said approach control relay and a 10 back contact of the track relay for said section next in advance.
